UNITED STATES PATENT OFFICE.

PAUL LEON PRICE, OF MOUNT VERNON, NEW YORK, ASSIGNOR TO IRVING IRON WORKS COMPANY, A CORPORATION OF NEW YORK.

STAIR TREAD.

Application filed January 8, 1925. Serial No. 1,142.

To all whom it may concern:

Be it known that I, PAUL LEON PRICE, a citizen of the United States of America, residing at Mount Vernon, county of Westchester, State of New York, have invented certain new and useful Improvements in Stair Treads, of which the following is a specification.

My invention relates to stairways and 10 steps in the form of metal gratings and more particularly comprises improvements by which the front portion of each such stair-tread may be easily distinguished in appearance from the next underlying tread, 15 and also the durability and strength of that portion of each tread, which of course is subjected to the greatest wear and load in use, may be increased.

Concurrently with the recently extended 20 use of ventilated floorings formed of grating in the buildings of many industrial plants, power houses, engine rooms and in similar structures, stairs and steps of similar construction have come into more extensive use. Objection is sometimes made 25 to the use of such gratings for stairs or steps on the ground that the whole structure is so skeletonized and permeable to light that a person looking down on the 30 stairs cannot always tell where one tread ends and another begins, and, if he mis-calculates his movements as the result of this uncertainty, he may miss his footing and experience a bad fall. My present invention 35 overcomes this difficulty by increasing the visibility of the front edge of each stair tread by making the grating along that edge in one or more spaces of finer, or closer or different mesh than is the remainder of the grating of that tread. The 40 front edge portion of each stair-tread being thus less permeable to light than the rear portion of the tread beneath it, the line of demarcation between any two successive 45 steps becomes thereby clear and easily discernible to any one walking or looking down the stairs or steps.

The best form of apparatus embodying 50 my invention at present known to me is illustrated in the accompanying sheet of drawings in which,

Fig. 1 is a plan view of a stair-tread with parts broken away,

Fig. 2 is an end elevation of the same, 55 parts being broken away,

Fig. 3 is a longitudinal section on line 3—3 of Fig. 1, parts being broken away, and

Fig. 4 is a perspective view, on a smaller scale, of a flight of stairs embodying the invention.

Throughout the drawings like reference characters indicate like parts.

Each stair-tread is usually composed of a rectangular frame of metal having longer 65 side pieces, 1 and 2, and shorter end pieces 3 and 4, and a panel of any desired form of grating placed within said frame. As here shown said grating consists of the parallel straight bars 8, 8, spaced apart by 70 reticulated strips 10, 11, all these being riveted or welded together or to adjacent portions of the surrounding frame. The ends of some or all of the straight bars may be supported by inwardly bent tongues of 75 metal 7, cut from the frame end pieces 3 or 4.

According to my invention certain of the straight bars 8, 8, nearest the frame side bar 1 (which is to form the front of the step or stair-tread) are preferably set more closely together than are the straight bars located at other portions of the tread, and the wider spacing is also preserved between the rearmost bar 8, and the back frame 85 bar 2. The result is, even if the rivet spacing is uniform throughout, that the front section 5 of each skeleton tread so formed presents a finer mesh of grating than does the rear portion 6 (see Fig. 4). Consequently when a series of such varied mesh gratings are set in supports 9, 9, to form a flight of stairs or ladder, as shown in Fig. 4, and one looks down said stairs, the successive treads do not appear to merge one 90 into another and form an expanse of grating of uncertain surface contour, as is sometimes the case when uniform mesh gratings are used throughout the stair-treads. On the contrary, when my invention is used, the finer or otherwise different mesh front edge of each tread, being less permeable to light or otherwise differentiated in appearance, is clearly defined and sharply contrasted against the wider or 95 other mesh rear portions of the next lower step which are more permeable to light or otherwise distinctive and present a different appearance. This brings out to the eye of the observer the successive stair-treads in 100 105 110

true perspective and the user can readily tell just where to place either foot in descending such a stairway.

Preferably I further add to this differentiation in the appearance and visibility of the front edge of each step by making the front frame bar 1 thereof thicker and heavier than is the rear frame bar 2.

Both the above described novel features 10 of construction also serve a useful purpose by increasing the wear resisting and weight sustaining qualities of the front portion of each stair tread or step, and this is important as that portion is always subjected 15 to much greater wear than are other portions of each tread, as the average user treads only on the front part of each step or stair, and are subjected to greater shocks if a heavy object is dropped on or rolls 20 down the stairs.

While I have illustrated a particular type of mesh in the grating shown and particular ways of fastening the structural elements together, it is to be understood, of course, 25 that the invention is not limited to these details but might be embodied in other forms of grating, with other forms of fastening and frames of other shape.

The reticulated strips 10, 10, between 30 those bars 8, 8, which are set closer together at the front of each tread are, of course, bent to a less degree than are the strips 11, 11, placed between the more widely spaced bars 8, 8, at the rear portion of each tread.

35 Having described my invention, I claim:

1. As a new article of manufacture, a grating adapted for use as a step, the mesh of which gratings while continuous, is of a

character next to one edge different from that throughout the remainder of the grating area. 40

2. As a new article of manufacture, an iron grating adapted for use as a stair tread, which said grating comprises a rectangular frame, a series of parallel straight bars extending lengthwise of said frame and a series of reticulated spacing strips between said bars, the bars nearest that side of the rectangular frame intended for the front of the step being spaced closer together than 50 are the remaining bars. 45

3. A combination such as set forth in claim 2 in which the portion of the rectangular frame forming the front of the step is thicker than the remainder of said frame. 55

4. A stairway having treads of grating, the mesh of that portion of the grating of each tread adjacent the front of the stairway being closer than that of the remaining portion of said tread whereby the relative 60 visibility of the front portion of each stair tread is increased.

5. A stair tread for use in skeleton stairways comprising a grating, the front portion of which grating inside of the outer 65 supporting bar for said grating contains a larger amount of metal per unit of superficial area; whereby it is made of stronger construction than are the rear portions of said grating. 70

6. A stair-tread for use in skeleton stairways comprising a grating the front portion of which tread is made of grating of a different mesh than that of which the other portions are composed.

PAUL LEON PRICE.
